UNITED STATES PATENT OFFICE.

JOSEPH MANDELL, OF SHERBROOKE, QUEBEC, CANADA, ASSIGNOR TO WALTER BLUE & CO. LTD., OF SHERBROOKE, CANADA.

MUFFLER ATTACHMENT FOR ULSTERS, OVERCOATS, CAPES, OR OTHER GARMENTS.

Application filed January 23, 1925. Serial No. 4,260.

This invention has relation to new and useful improvements in muffler attachment for ulsters, overcoats, capes or other garments and has for its primary object the provision of an attachment of this character which may be readily secured upon or removed from the garment as desired and which is mounted thereon in such a manner that the muffler may be readily adjusted with the single thickness or double thickness extending above the ulster collar and around the neck either when the garment collar is folded down or turned up, as desired.

The invention has for another object the provision of the muffler attachment of the character stated which is provided with means for detachably attaching the muffler to the garment in such a manner as to retain the muffler in position, near the edge of the ulster garment collar so that when in normal position, the muffler will not be seen when the garment is worn but may be readily brought to operative position as desired.

A further object of the invention resides in the provision of novel means for securing the muffler in proper position on the inner side of the ulster garment and along the collar and lapel portion thereof so that the muffler will hang properly either when in use or when in inoperative position and hid.

With the foregoing and other objects in view, as will appear as the description proceeds, the invention consists in the novel construction, combination and arrangement of cooperating elements as hereinafter more specifically set forth, claimed and shown in the accompanying drawings forming part of the present application and in which:

Figure 1 is a view showing the garment in use, the garment being shown in dotted lines.

Figure 2 is an elevation of a garment provided with attaching means for the muffler, the view showing the inner side of the garment.

Figure 3 is a plan of the muffler folded and showing the attaching strip carried thereby.

Figure 4 is a transverse section of the muffler showing the attaching strip extending at right angles from one side of the muffler.

Figure 5 is a view similar to Figure 4, showing a slightly modified form of the invention. 55

Figure 6 is a transverse section through a further modified form of the invention.

Figure 7 is another view similar to Figures 4 to 6 inclusive, showing a further modified form. 60

Figure 8 is a fragmentary detail view, partly in section, showing the muffler attached to the garment, and both sections of the muffler raised above the collar of the rest. 65

Figure 9 is a view similar to Figure 8, showing only one section or one half of the muffler in raised position.

Figure 10 is a view similar to Figures 8 and 9 showing the muffler in normal position, with both sections or halves thereof dropped down so as to be hidden by the garment collar when the garment is in use and the muffler is not required. 75

Referring more in detail to the drawings in which similar reference characters designate corresponding parts throughout the several views, it will be noted that the muffler 11 has a central longitudinal attaching strip 12 secured by one longitudinal edge to one side which, may be termed the inner side of the muffler 11. The attaching strip 12 is secured in position centrally and longitudinally of the muffler 11 and for the greater portion of the length thereof in either direction from the center of the muffler 11 by a row of stitching 13. The attaching strip 12 is then folded back over the attached edge and a second row of stitching 14 is extended through the folded-back portion of the attaching strip 12 and through the muffler 11, the row of stitching 14 being parallel with and close to the row of stitching 13, as shown clearly in Figure 4 of the drawings. A series of spaced buttonholes 15 are provided in the attaching strip 12 so that the attaching strips 12 may be readily secured in position by the buttons 16, fasteners, snaps or other appropriate securing means arranged on the inner side of the garment 17 to which the muffler is to be attached and along the collar and lapel portions thereof. It is to be noted from Figure 2 that nine buttons are preferably employed, with three of them arranged practi-

2
 cally in alignment near the edge of the center portion of the collar 18. Then three of the remaining buttons 16 are arranged in equally spaced relation along either lapel portion of the garment the uppermost button of each of the last mentioned series of buttons being slightly further from the rolled over edge of the lapel than the adjacent button of the upper series and the 5 second and third or lower buttons of each of these lapel series being brought in still further from the rolled edge of the lapel, as shown clearly in Figure 2. By arranging the buttons in this manner, the muffler will 10 be properly supported so that it will be out of sight when not in use but when required for use may be readily raised on the attaching strip 12 with one or both sections or 15 halves of the muffler extended above and over the rolled portions of the lapels and 20 collar of the garment, as shown in Figure 1. As will be noted from Figures 1 to 4 inclusive, the manner of fastening the attaching strip 12 onto the muffler 11 will permit 25 folding of one section or one half of the muffler onto the other while the two sections or halves are in use or not in use, or extension of one section or one half of the muffler beyond the rolled edge of the collar 30 and lapels of the ulster, while the other half or section of the muffler remains in its normal depending or dropped position within the garment and covering over the attaching strip 12.

35 By referring to Figure 8, it will be seen clearly how both sections or halves of the muffler may be extended upwardly over the rolled edge of the collar and lapels of the garment while Figure 9 shows only one section or half of the muffler turned up and the other in its normal depending position completely covering the attaching strips 12. In Figure 10 the muffler is illustrated in its normal position where it is out of use and both sections or halves depending inwardly of the rolled edge of the collar and lapels.

40 In the modified form of the invention shown in Figure 5, the longitudinal central portion of the muffler 11^a is brought together to form a double rib 20^a on one face of which is secured the attaching strip 12^a by two or more rows of stitching 21, the attaching strip 12^a being extended longitudinally of the rib 20^a, as will be readily understood by 45 referring to the drawings. It will also be

apparent that only one longitudinal edge portion of the attaching strip 12^a is secured to the rib 20.

In the modified form of the invention shown in Figure 6, the muffler 11^b is illustrated in double thickness with the longitudinal central portion of one of the thicknesses bent upon itself and brought together to form the rib 20^b of double thickness. This form also discloses the attaching strip 12^b as being formed of double thickness with the inner longitudinal edge bifurcated or separated and secured on opposite sides of the rib 20^b by a suitable number of rows of stitching 22 extended through the rib 20^b and through both portions of the attaching strip 12^b. 60 65 70

In the modified form shown in Figure 7, the muffler 11^c is shown as being of single thickness with its longitudinal center brought together and extended from one side to form the rib 20^c of double thickness. An attaching strip 12^c similar to the attaching strip 12^b is employed with the separated portions at the inner edge engaged over the 75 80 85 opposite sides of the rib 20^c and secured thereto by rows of stitching 23.

While the preferred forms of the invention have been disclosed and it is believed the complete construction and operation of 85 the muffler attachment for the garment may be readily understood from the foregoing paragraphs taken in connection with the accompanying drawings, it is to be understood that minor changes in the details of the construction, combination and arrangement of the cooperating elements may be resorted to within the scope of what is claimed, without departing from the spirit of the invention. 90 95

What is claimed is:—

The combination with a garment and a muffler, of an attaching strip secured by one longitudinal edge to the longitudinal center of one face of said muffler and attaching members carried by the garment along the 100 collar and lapel portions thereof, and on the inner face of the garment with the attaching members along the lapel portions gradually receding, as they proceed downwardly, from the rolled edges of the lapel portions 105 of the garment; the attaching strip being adapted for detachable engagement with said attaching members.

In testimony whereof I affix my signature.
 JOSEPH MANDELL.
